United States Patent Office

Des. 220,080
Patented Mar. 9, 1971

220,080

BAIL

William Doyle Watt, Jr., Grand Rapids, Mich., assignor to Keeler Brass Company, Grand Rapids, Mich.

Filed Dec. 5, 1969, Ser. No. 20,386

Term of patent 14 years

Int. Cl. D8—03

U.S. Cl. D8—138

FIG. 1.

FIG. 2.

FIG. 3.

FIG. 1 is a front view of a bail;

FIG. 2 is a sectional view of my design, taken along lines II—II of FIG. 1; and

FIG. 3 is a partial sectional view of my design, taken along lines III—III of FIG. 1.

I claim:

The ornamental design for a bail, as shown.
